United States Patent Office

Des. 193,194
Patented July 10, 1962

193,194

CABINET

Warren R. Black, Grand Rapids, Mich., assignor to American Seating Company, Grand Rapids, Mich., a corporation of New Jersey

Filed Oct. 6, 1960, Ser. No. 62,393

Term of patent 14 years

(Cl. D33—19)

Fig. 1

Fig. 2

Fig. 3

FIGURE 1 is a front perspective view of a cabinet, showing the new design, the cabinet being here shown in fully closed condition;

FIGURE 2 is a perspective view of the cabinet with the side door thereof open to reveal the lower interior of the cabinet;

FIGURE 4 is a front perspective view of the new cabinet with the top thereof swung to open position to reveal the upper interior of the cabinet; and

I claim:

The ornamental design for a cabinet, substantially as shown.
